UNITED STATES PATENT OFFICE.

CHARLES O. CONNER, OF HEPPNER, OREGON.

STREET-CAR FENDER.

No. 868,845.

Specification of Letters Patent.

Patented Oct. 22, 1907.

Application filed March 13, 1907. Serial No. 362,199.

To all whom it may concern:

Be it known that I, CHARLES O. CONNER, a citizen of the United States, residing at Heppner, in the county of Morrow and State of Oregon, have invented a new 5 and useful Street-Car Fender, of which the following is a specification.

This invention relates to fenders for use on street cars and the like, and has for its principal object to provide an improved form of fender which will normally be held in elevated position clear of ordinary 10 track obstructions, and which will be automatically lowered to operative position before reaching an object on the track.

A further object of the invention is to provide a suitable 15 means for automatically releasing and lowering the fender, and further to provide a structure which is under the control of the motor man or other attendant on the car in case the automatic releasing mechanism fails.

20 With these and other objects in view, the invention consists in certain novel features of construction and arrangement of parts, hereinafter fully described, illustrated in the accompanying drawing, and particularly pointed out in the appended claims, it being understood 25 that various changes in the form, proportions, size and minor details of the structure may be made without departing from the spirit or sacrificing any of the advantages of the invention.

In the accompanying drawings:—Figure 1 is a perspective view of a fender constructed in accordance 30 with the invention. Fig. 2 is a side view, partly in section, of the same. Fig. 3 is a detail sectional view of the joint between the release or trip frame and the rock shaft. Fig. 4 is a similar view of the joint between 35 the members of the fender braces. Fig. 5 is a detail section showing an end view of the locking pin by which the members of the fender brace are held in their normal positions.

Similar numerals of reference are employed to indicate 40 corresponding parts throughout the several figures of the drawings.

Secured to the front sill of the car platform is a pair of vertically disposed tubular guides 10 which are supported in position by braces 11 and such other fastening 45 devices as may be necessary.

Mounted slidably in the tubular guides 10 is a pair of vertical bars 15 from the rear ends of which project horizontal arms 16, and the forward ends of these arms are connected to the upper ends of the bars 15 by obliquely disposed braces 17. The forward ends of the 50 arms are further connected by a cross bar 18, and leading rearward from this cross bar is a receiving cage or basket 20 including side arms 21, a cross bar 22, and a plurality of small bars or wires 23 which preferably 55 are slightly elastic in order that a person or object may be received within the basket without severe shock.

The fender is normally maintained in an elevated inoperative position by a latch bar 25, which is slidably mounted in a recessed guide block 26 and extends under a tongue 27 that projects rearward from an inclined bar 28 carried by the fender. The latch bar 25 is pivotally connected to a crank 30 carried by a rock shaft 31 that is mounted in suitable bearings 32 arranged under a car platform, and when this shaft is rocked in the proper direction, the latch bolt will be withdrawn and the fender will be allowed to drop to operative position by gravity, or suitable springs or the like may be employed to assist the movement. The downward movement of the fender is limited by engagement of the upper enlarged end of the braces 17 with the top of the guides 10.

Both ends of the rock shaft 31 are provided with cranks 34, and to these cranks are connected a pair of inclined arms 35 that project some distance forward of the fender proper and are connected by a bar 36, 75 this bar being generally disposed five or six inches above the roadbed, and being maintained in place by a pair of chains 37, or similar supports.

Both the releasing bar 36 and the fender are normally maintained in a position some distance above 80 the road bed in order to clear ordinary obstructions, but in case of a person or a large object on the track, the releasing bar 36 will be engaged and forced rearward, thus turning the rock shaft 31 and withdrawing the releasing bolt 30, so that the fender may drop to 85 operative position in readiness for receiving the object or person before passing under the car.

In order to place the device under the control of the motorman, the rock shaft is provided with a rearwardly extending rocker arm 40 that is connected to 90 a vertically disposed treadle bar 41 having a foot piece 42 arranged slightly above the platform and within convenient reach of the motorman or other attendant.

To provide for the folding of the fender and trip frame, it is desirable to employ means by which the 95 arms of the trip frame may be disconnected from the rock shaft and means whereby the braces of the fender frame can be folded, the fender frame thus being hingedly mounted so that it may be arranged in a vertical position, as indicated by dotted lines in Fig. 2. To 100 this end the arms 35 of the trip frame are provided with studs 43 for reception by sockets 44 in the ends of the rock shaft, spring actuated keys 45 being employed to engage groove 46 in said stud. By withdrawing the key against the tension of the spring 47, the studs or 105 heads of the arms 35 can be withdrawn from the sockets 44, and the trip frame may then be disposed in a vertical position close to the front of the car, or parallel with the folded members of the fender proper.

The arms 16 of the fender frame are hinged at 48 to 110 the uprights, and the braces 17 are joined at 49, the upper ends of said braces being hinged as at 50 to the

uprights 16, the means for holding the braces rigid when in their extended or normal positions being illustrated in the drawing as consisting of a pin 51 engaging registering guides 52 and 53 on the members 5 of the brace, said rod being provided at one end with a grip or handle 54, and at the other end with a key ward or ear 55 which is adapted when turned to one position to register with a slot 56 in the guide 53 to permit of the withdrawal of the pin from said guide 10 52, but normally held from displacement or withdrawal by the engagement of said ward or ear with the outer extremity of the guide 53. Obviously when the pin is withdrawn from the guide 53, the joint 49 can be broken to permit the folding of the brace.

15 I claim:—

1. In a car fender, a vertically movable receiving cage or basket, vertically disposed guides therefor, said basket including a frame formed of hingedly connected members, and a pair of hinged braces to permit folding to a position flat against the front of the car, a latch bar serving as a support for the fender, a rock shaft connected to the latch bar, and a releasing bar connected to the rock shaft and extended forward of the fender for preliminary engagement with an object on the track.
- 20 2. In a car fender, a receiving cage or basket having ver-

45 tically arranged side bars, tubular guides supported by the car and arranged to receive said side bars, side bar braces having enlarged heads serving by engagement with the tops of the tubes to limit downward movement of the cage or basket, a latch bar normally holding the cage or basket in elevated position, a cranked rock shaft journaled under the car and connected to the latch bar, and a U-shaped releasing bar extending forward of the fender and having its side arms connected to said rock shaft.

3. In a car fender, a pair of tubular guides arranged in front of the car platform, a basket having vertical side bars connected to said tubular guides, bracing bars connected to the side bars and having enlarged heads forming stops for limiting downward movement of the basket, a rock shaft journaled under the car and provided with 40 cranks, a latch bar connected to one of the cranks and serving to maintain the basket in elevated position, a U-shaped releasing bar extending forward of the basket and having its side arms connected to the rock shaft, a rocker arm extending from said shaft, and a treadle bar connected to the rocker arm and extending through a guiding opening in the car platform.

In testimony that I claim the foregoing as my own, I have hereto affixed my signature in the presence of two witnesses.

CHARLES O. CONNER.
